FIG. 16.

UNITED STATES PATENT OFFICE.

GUSTAV GOLDMAN, OF BALTIMORE, MARYLAND.

DIE-PRESS.

No. 835,753.

Specification of Letters Patent.

Patented Nov. 13, 1908.

Application filed September 29, 1904. Serial No. 226,594.

To all whom it may concern:

Be it known that I, GUSTAV GOLDMAN, a citizen of the United States, and a resident of Baltimore, Maryland, have invented a new and useful Improvement in Die-Presses, which is fully set forth in the following specification.

This invention relates to mechanism designed to cut out from a sheet or band of material continuously fed thereto pieces or portions of said material of any desired pattern or outline.

While the machine hereinafter described is capable of a variety of uses of the general character indicated, it is particularly designed for cutting garment-pads from continuous sheets of fibrous material. The same is designed for use in connection with any material capable of being acted upon by a die knife or cutter impressed against a suitable platen, though in the manufacture of garment-pads it is designed to operate more particularly in connection with sheets or strips of fibrous material.

While, as intimated above, the apparatus is capable of a great variety of uses, its use as a means for cutting garment-pads from fibrous material will be specifically described herein for the purpose of illustrating the invention and which description and illustration will be sufficient to suggest to those skilled in the art its adaptability to other analogous arts.

In my United States Patent No. 758,243, as well as other patents taken out by me, I have described a process of forming a sheet of fibers matted or felted together. The die press or cutting apparatus forming the subject-matter of the present application may be used for making pads from any suitable fibrous material, preferably, however, the material made as described in my aforesaid patent being employed.

The objects of the invention are to provide means for feeding a continuous strip of material to a suitable cutter, which will act to cut the material into the desired form or pattern, and in some instances also act to automatically convey the articles thus cut from the band or strip away from the machine.

In my United States application, Serial No. 226,226, filed September 27, 1904, I have shown a means of skiving or cutting away a portion of the surface of a continuously-advancing sheet or strip of fibrous material in such way as to leave said sheet composed of a

series of portions which are so formed or tapered as to particularly suit them for having garment or other pads cut therefrom, the tapering surface of each of said portions being such that after the pad is cut according to the desired outline it will have the correct or desired taper in the several directions without the necessity of further skiving off or building up any particular portion in order to give it the proper contour.

One of the objects of the present invention is to provide a machine for cutting garment-pads from a strip of fibrous material skived or cut out, as indicated, which machine shall operate in combination with said skiver, the strip or band of fibrous material being fed from the skiver immediately to the cutting-machine.

The particular mechanical expression of the inventive idea illustrated in the accompanying drawings is one in which a stationary hollow cutting-die has the skived sheet of fibrous material forced against its cutting edges by the action of an intermittently-vibrating platen, the skived sheet of fibrous material being fed between the stationary die and the vibrating platen by the action of suitable feed-rollers intervening between the skiver and the die of the cutting-machine, which I shall hereinafter designate as the "die-press." When the platen is advanced against the cutting-die, the forward movement of the sheet of material is necessarily interrupted for a fraction of time, while the same sheet of material is continuously advanced from the skiver toward the die-press. Moreover, it is essential that the skived sheet should be fed to the cutter-die so that the skived portions will be properly positioned with relation to the die, and for this purpose the movement of the skiver and of the die-press must be so timed that the sheet of material will be advanced through the skiver and to the die-press in such a way as to bring the skived portion into proper position before the die of the die-press.

With this object in view the invention further consists in the combination of a skiving-machine and a cutting-machine or die-press with means continuously feeding the skived sheet from the skiver and intermittently feeding said sheet to the die-press, the whole proceeding as one continuous and automatic operation.

Furthermore, the invention consists in intermittently operating feed-rollers for feed-

ing the skived sheet to the die-press and means for adjusting said rollers with relation to the die, whereby the skived sheet may be initially adjusted so as to bring the desired portions thereof in proper relation to the die of the die-press. One means for adjusting these rollers consists of bearings therefor in a pair of vertically-adjusted racks with pinions for operating said racks and a hand-wheel controlled by a pawl and ratchet for operating the pinions.

The inventive idea involved in the cutting machine may be embodied in various mechanical forms, one of which forms is shown in the accompanying drawings for the purpose of illustrating the invention, reference being had, however, to the claims for defining the limits of said invention.

In said drawings, Figure 1 is a side elevation of the die-press, together with the timing-cam on the skiver for enabling the skiver and the die-press to be operated in unison. Fig. 1^a is an enlarged sectional detail of the driving-shaft clutch. Fig. 2 is a side elevation of the skiver and die-press combined. Fig. 3 is a front elevation of the die-press. Fig. 4 is a perspective view, partially in dotted outline, illustrating the means for starting and stopping the die-press, whereby its intermittent action is secured and the means on the skiver whereby such starting and stopping devices are controlled. Fig. 4^a is an enlarged detail of the starting and stopping device shown in Fig. 4. Fig. 5 is a plan view of a portion of the starting and stopping devices shown in Fig. 4. Fig. 6 is a left-hand elevation of Fig. 5. Fig. 7 is a top plan view of the intermittently-operating feed-rollers of the die-press. Fig. 8 is a section on the line 8-8 of Fig. 7 looking in the direction of the arrow. Fig. 9 is an illustration in detail perspective of a certain portion of the starting and stopping mechanism illustrated in Figs. 4, 5, and 6. Fig. 10 is a perspective view of the means for adjusting the intermittently-operating feed-rollers with relation to the die, a guide-apron for the sheet of material being also shown. Fig. 11 is a side elevation of Fig. 10. Fig. 12 is a front elevation of the feed-rollers, their adjustable bearings, and the guide-apron, a strip of fibrous material being shown in the act of being advanced in front of the die. Fig. 13 is a perspective view of a pair of ejecting-plates operating in connection with the platen to push the pads through the hollow die, together with the mechanism for intermittently operating said plates. Fig. 14 is a detail perspective of means for cushioning the blow of the mechanism when the same is stopped, the same forming a part of the intermittently starting and stopping devices shown in Fig. 4. Fig. 15 is a sectional detail showing the operation of the feed-rollers and apron, the cutting-die, the platen,

the ejecting-plates, &c., the parts being shown in the position which they occupy just prior to the advancement of the platen against the cutting-die. Fig. 16 is a like view showing the parts in the position they occupy just after the platen has forced the sheet of fibrous material against the die, showing the ejector-plates in the act of ejecting a pair of pads from or through the hollow die.

Referring to the drawings, 1 is any suitable framework for the machine, upon which is rigidly mounted, preferably in a vertical position, a hollow die or cutter 2 and a vibrating platen 3. The die may be of any suitable outline or pattern desired and may be formed to cut either a single or a plurality of pads or other articles at each stroke or vibration of the platen. As here shown, reference being particularly had to Figs. 12, 15, and 16, the die 2 is approximately heart-shaped and has a dividing cutter-blade 4 extending transversely across it in such way as to cause it to cut at a single vibration of the platen two pads substantially identical in shape. The platen 3 is supported on links 5, pivoted to the frame 1 at 6 and to the sides of the platen at 7, so that when power is suitably applied thereto the links 5 move forward, carrying the platen with them up against the cutting edge of the die 2. For the purpose of imparting the vibrating movement to the platen links 8 are pivoted to the platen at 7 and are eccentrically pivoted at 9 to gear-wheels 10 10, Fig. 4, keyed to the shaft 11, turning in bearings 12 on the framework of the machine. The large gear-wheels 10 10 mesh with pinions 13 13, keyed to shaft 14, upon one end of which are two pulleys 15 16, 15 being fast to shaft 14 and 16 being loose thereon. The power for operating the platen is derived from a belt 17, extending from any suitable power-shaft, When the driving-belt is on the pulley 15, the platen will be vibrated toward and from the die 2 and when the belt is shifted from the pulley 15 to the pulley 16 the machine will stop.

The machine herein described may be employed to cut pads or other articles from any suitable strip of material, whether said strip is a flat one of even thickness or is one of uneven thickness especially prepared for the purpose of forming the pad or other article which it is desired to make. One of the uses to which it is particularly adapted is that of cutting garment-pads from a strip of fibrous material especially prepared for the purpose, and in the manufacture of such garment-pads it is found advantageous to combine the die-press with the machine for skiving or cutting out sloping and approximately transverse channels on one side of the strip of material to be treated. The same may be combined with any skiving-machine adapted for

this purpose. As here shown, it is combined with a skiver of my invention, consisting of a roller 18, Fig. 2, having depressions 19 formed in its surface and a pressure-roller 20 acting to hold the strip of fibrous material 21 in contact with the surface of the pattern-roller 18, and a transversely-moving cutter-blade 22, which serves to skive out or cut off that portion of the sheet 21 which is forced into the depression 19 of the pattern-roller 18 as the sheet 21 is advanced.

The specific construction of skiver is not claimed herein, since it forms the subject-matter of my United States application, Serial No. 226,226, filed September 27, 1904, the same only being claimed in combination with the die-press.

The strip of fibrous material 21 after it has been treated by the skiver is continuously advanced toward the die-press by two feed-rollers 23 and 24 on the skiver and is received by a pair of feed-rollers 25 and 26 on the die-press, these rollers being situated above the die and in such position that as the band of fibrous material 21 advances downward between them it will pass in front of the platen and between it and the cutter or die, all of which will be clearly understood from an inspection of Figs. 15 and 16.

In order that the pads may be properly cut from the skived portions of the material 21, it is essential that the medial or dividing blade 4 of the cutter should cut transversely across the thickest or highest portion 27, Fig. 2, of the skived-out sheet of fibrous material, the upper and lower edges of the cutter cutting through the sheet of fibrous material at the hollowed out or thinner portions 28 of the fibrous sheet. In order that the sheet of fibrous material may be so fed to the cutter-die as to bring the parts 27 and 28 in the desired position, the feed-rollers 25 and 26 are arranged to be adjusted up or down, as may be required, since with different-sized dies or cutters or with different patterns or outline of pads it will be necessary to alter the relation between the feed-rollers and the die or cutter. The vertical adjustment of the rollers is secured by mounting them in bearing-plates 29, secured to rack-bars 30, which rack-bars are secured in position on the fixed part of the framework of the machine by headed screws 31 extending through slots 32 in the framework of the machine and into the rack-bars 30, as will be readily understood from an inspection of Figs. 10 and 11. The headed screws 31 act to hold the rack-bars against the slotted framework of the machine, while at the same time leaving said bars free to move up and down within the limits of slot 32. Rack-bars 30 are engaged by a pair of pinions 33, keyed to the shaft 34, which shaft has on its outer end a ratchet-wheel 35, engaged by ratchet 36, held in contact therewith by spring 37. The

ratchet-wheel 35 can be turned by the crank-arm 38 to elevate or depress the rack-bars 30, and this without regard as to whether the die-press is at rest or in operation.

Referring to Fig. 11, it will be seen that the roller 25 has its bearing in one end of the bearing-plates 29, carried by the rack-bars, and that the roller 26 has its bearing in the opposite end of said bearing-plates, the shaft of the roller 26 taking bearing in a slot 29' in the bearing-plate 29, a spring 39 having one end secured to the shaft of the roller 26 and the other end to the rack-bar 30. The two rollers 25 and 26 are geared together by intermeshing pinions 40 41, but in case a sheet of fibrous material of any unusual thickness passes between the rollers the spring 39 yields to permit it to pass, subsequently drawing the gears on the two rollers again into mesh, as shown in Fig. 11. Power is applied to drive the feed-rollers by means of a pulley 42, Fig. 3, secured to the end of the shaft on the roller 25, around which pulley 42 extends a belt 43, Fig. 1, passing over one member of a clutch 44, belt 43 passing over that member of the clutch which is loose upon the driving-shaft and only acting to drive the feed-rollers 25 and 26 when the loose member of the clutch is thrown into engagement with the other member thereof secured to the shaft. The particular construction of this clutch is immaterial. Any clutch which has an idle and a fast member capable of being shifted into and out of engagement with each other will be suitable for the purpose.

For the purpose of guiding the sheet of fibrous material in its downward path after it leaves the feed-rollers 25 and 26 an apron 45 is pivotally mounted to swing on the shaft 34. (See Figs. 10 and 12.) This apron is preferably made of metal and has a lower cut-out portion 46, whose outline substantially conforms to that of the upper portion of the die or cutter. Opposite to the apron 45 is an idling-roller 47, Fig. 11, mounted in suitable bearings upon the framework of the machine, and suitable belts or bands 48 extend over the roller 25 and the idling-roller 47, the roller 25 preferably having grooves cut in its surface, so that the belts or bands 48 lie flush with the surface of the roller. It will be seen that as the sheet of skived material 21 is fed downward from the feed-rollers 25 and 26 it passes between the belts or bands 48 on one side and the apron 45 on the other and is thereby guided into its position in front of the die or cutter 2.

The feed-rollers 25 and 26 are intermittently operated, being set in motion to feed the fibrous band downward between the platen and the cutter during the time when the platen is withdrawn from the cutter and at rest and being interrupted in their feeding action during the time when the platen is

advanced against the cutter. It will therefore be seen that the feed-rollers act to feed or advance the sheet of fibrous material to the die-press as the same is needed, the action 5 of the rollers and of the platen being timed for this purpose and the rollers being adjusted vertically to bring the skived sheet into proper position before the cutter.

While the action of the feed-rollers 25 and 26 is intermittent, that of the feed-rollers 23 and 24 upon the skiving-machine is continuous, and it necessarily results that during the time the feed-rollers 25 and 26 upon the die-press are at rest the rollers 23 and 24 upon 15 the skiver will act to advance a determined portion of the fibrous strip, which will thus sag down between the two machines. In order that this sag in the advancing strip of fibrous material may be eliminated at each 20 operation of the feed-rollers upon the die-press, the driving belt and pulleys therefor are so arranged as to drive the feed-rollers 25 and 26 upon the die-press at a more rapid rate than that of the feed-rollers 23 and 24 25 upon the skiving-machine, so that when the feed-rollers on the die-press are set in operation they quickly take up the sag in the sheet of material and advance the lower end of said sheet into the proper position between the platen and the die. This sheet of 30 fibrous material, however, which is preferably employed in the formation of pads and similar articles, is not one of great tensile strength, and therefore is not capable of 35 withstanding great longitudinal strain, and it is important that the rapid advance motion of the feed-rollers of the die-press should be interrupted before any strain is put upon the fibrous sheet 21. For the purpose of 40 avoiding any such strain there is mounted on the shaft of the feed-roller 25 of the die-press an idling sprocket-wheel 49, (see Fig. 7,) which sprocket-wheel is between the pulley 42 and roller 25. This idler-sprocket is 45 provided with a tooth 50, projecting laterally from its hub immediately in advance of a tooth 51, projecting from the side of the pulley 42.

Passing around the idler-sprocket 49 is 50 a sprocket-chain 52, which gears with a sprocket-wheel 53 on the shaft 54 of the feed-roller 24 of the skiving-machine. Since the idler-sprocket 49 is thus geared by means of the sprocket-chain 52 to the sprocket-wheel 55 on the shaft of the feed-roller 24 on the skiver, it will be apparent that the idler-sprocket 49 will be in perfect time with the feed-roller 24, and during the time in which the feed-roller 25 on the die-press is at rest 55 60 the tooth 50 on the idler-sprocket will move away from the tooth 51 upon the pulley 42. The parts are so timed that this advance of the tooth 50 from the tooth 51 is always less than one revolution. When the clutch 44 is 65 thrown so as to operate the feed-rollers upon

the die-press, the pulley 42 by reason of its more rapid rate of movement quickly causes the tooth 51 to overtake and impinge upon the tooth 50 on the idler-sprocket 49. It will be seen that this will occur exactly at 70 the time when the feed-rollers 25 and 26 shall have moved sufficiently to take up the slack in the fibrous sheet that has occurred during the period of rest of the feed-rollers 25 and 26. The driving-belt for the pulley 42 is 75 made just loose enough so that when the tooth 51 engages the tooth 50 the belt will slip on the pulley 42 or upon the driving-pulley therefor, and therefore will yield to the resistance offered by the tooth 50, the 80 sprocket-chain 52 and the mechanism for propelling the feed-roller 24 upon the skiver. It follows that after the tooth 51 has overtaken the tooth 50 the two will move forward together until the operation of the feed-rollers 25 and 26 is again interrupted. 85

As hereinbefore stated, the platen is operated when the driving-belt 17 is shifted to the pulley 15 and is stopped when the belt is shifted back from the pulley 15 to the idler-pulley 16. For the purpose of shifting the belt 17 an ordinary belt-shifter 55, Fig. 4, is mounted to slide in guides 56 57 on the rear of the frame 1 of the machine, to which slide is attached a spring 58, whose tension 90 acts to throw the belt from left to right—i. e., to throw the belt onto the pulley 15 in position to set the machine in motion. The bell-crank lever 59 has one of its arms connected by a pin-and-slot connection 60 to the belt-shifter 55, the other arm being pivotally connected at 61 to a lever-arm 62, which extends along the side of the die-press. The bell-crank lever 59 is pivoted to the framework of the machine at 63 and the lever-arm 62 is 95 pivoted at 64 to a vertical lever 65, which latter lever is in turn pivoted to the framework of the machine at 66. The upper arm of the lever 65 extends upward into proximity to the right-hand gear-wheel 10 of the die-press, 100 as clearly shown in Fig. 4. The pivotal connection between the lever 65 and the lever-arm 62 is of a pin-and-slot character, which permits the lever-arm 62 to have a slight vertical movement with relation to the lever 65. 105 The lever-arm 62 extends forward in the direction of the skiver and is provided on its end adjacent to the skiver with a lug 67, Fig. 4^a, having a catch-shoulder 68, which when the parts are in the position shown in Fig. 4 engages with a corresponding shoulder 69 in a slot 70, formed in a forked guide 71, secured to the frame of the skiver, as will be understood from an inspection of Figs. 2, 4, and 4^a. When the lug 67 rests with its shoulder 68 in 110 engagement with the shoulder 69 in the slot 70, the parts are held in the position shown in Fig. 4 against the tension of the spring 58—i. e., in a position to hold the belt upon the idler-pulley, and consequently the machine is 115 120 125 130

at rest. When the lever-arm 62 is lifted so as to disengage the shoulder 68 of the lug 67 from the shoulder 69 in the slot 70, the spring acts to throw the belt-shifter, and thus shifts the belt from the pulley 16 to the pulley 15 and starts the machine.

For the purpose of disengaging the lever-arm 62 from the catch-shoulder 69 a trip is provided, which is located upon the skiver 10 and is actuated thereby, the tripping action being timed so as to occur once for each skiving action of the skiving-machine, thereby insuring that the platen of the die-press shall be advanced and one cutting action performed for each skived portion of the sheet of fibrous material 21. When the skiver is provided with a skiving-roller of the character shown in Fig. 2—i. e., one designed to effect two skives for each revolution of the skiving-roller—the trip is actuated twice by the skiver for each revolution of the roller and the platen of the die-press is advanced twice for each revolution of said skiving-roller. This construction is illustrated in Figs. 2 and 4, in which the trip for the lever-arm 62 is shown in the form of a swinging link 72, pivoted at 73 to a lever 74, which lever is pivoted at 75 to any suitable support—as, for example, the framework of the skiving-machine. (See Fig. 2.) The lower end of the swinging link 72 is guided in the forked guide 71 and is provided with a notch 76, into which the rear end of the lever-arm 62 is thrown when in its rearmost position, the swinging link 72 being held in operative relation with the end of lever 62 by a spring 77. The arm of the lever 74 opposite to the pivot-point 73, where said arm is connected to the link 72, extends rearward adjacent to the end 40 of the shaft of the skiving-roller 18, and this shaft has secured thereto a plate or bar 78, (see Figs. 1, 2, and 4,) which carries a pair of pins 79, eccentric to the skiving-roller 18. The rearward end of the lever 74 is so positioned that each of the pins 79 strikes it once during each revolution of the skiving-roller, thus depressing the rear end of the lever 74 and elevating the opposite end of said lever, and with it the tripping-link 72, thereby freeing the shoulder 68 on said lever from the shoulder 69 in the forked guideway and permitting the shifter 55 to be thrown by the spring 58, so as to start the machine.

The right-hand gear-wheel 10 upon the machine is provided with a projecting-lug, preferably in the shape of an antifriction-roller 80, Fig. 4, which as the gear-wheel 10 revolves engages the upper end of the lever 65 and throws it to the rear, and since this lever is connected at 64 to the lever-arm 62 and through said arm and the bell-crank 59 to the bell-shifter 55, the rearward movement of said lever 65 acts to throw the shifter from left to right against the tension of the spring 58, thereby again shifting the belt from

the pulley 15 to the pulley 16 and stopping the machine. When the lever 65 is thus thrown to the rear by the antifriction-roller 80 on gear-wheel 10, the shoulder 68 is again thrown into position to engage with the shoulder 69 in the guideway 70, the rear end of the lever-arm 62 contacting with the cut-out portions 76 of the swinging link 72 and the parts are in position to be again tripped by the action of the tripping-pin 79, controlled by the skiving-roller. The antifriction-roller 80 is so positioned on the gear-wheel 10 as to shift the lever 65 to the rear just before the platen has been advanced to its rearmost position—i. e., to the position in which it is withdrawn from contact with the cutter-die 2. The parts of the machine are necessarily quite heavy, owing to the necessity for strength, and the sudden stopping of such parts when in rapid motion would be liable to introduce unnecessary strains and possibly breakage unless the stopping action was cushioned, and for this purpose there is provided a stop in the shape of a bell-crank lever 81, Figs. 4 and 14, pivoted at 82 to the frame of the die-press, the lower arm of said bell-crank lever being pivotally connected by a pin and slot 83 to the lever-arm 62 and the other arm of said bell-crank lever 81 being provided with a stop-shoulder 84 in position to be engaged by a pin 85, projecting from the side of the right-hand gear 10 of the die-press. Pivoted to said bell-crank lever 81 in close proximity to the shoulder 84 is a stop-lever 86, whose lower end when the machine is in motion is in position to be engaged by the pin or lug 85 upon the gear-wheel 10, the upper end of the lever 86 being secured to one end of a stiff spring 87, whose other end is secured at 88 to the bell-crank lever 81. When the lug 85 strikes the lower end of the lever 86, it forces it rearward against the tension of the stiff spring 87 until such lower end of lever 86 contacts with shoulder 84 on bell-crank lever 81, the stoppage of the machine thus being cushioned by the tension of the stiff spring 87. The lever 86 is provided with a pin 89, which projects from its side over the top of the arm of the bell-crank lever 81, and thereby acts as a stop to prevent the spring 87 from withdrawing the lever 86 so far to the rear as to bring it out of the path of the pin 85 upon the gear-wheel 10. When the pin 80 on the gear-wheel 10 engages the lever 65, and thereby forces the lever-arm 62 rearward for the purpose of shifting the belt and stopping the machine, the bell-crank lever 81 is rocked, so as to depress that arm which has the shoulder 84 and carries the lever 86 and spring 87, thereby bringing said lever and shoulder in the path of movement of the pin 85. On the other hand, when the spring 58 acts to throw the belt-shifter so as to start the machine the bell-crank lever 81 is actuated so as to lift the arm having the shoulder 130

84, and with it the lever 86 and spring 87, out of the path of the pin 85, thereby leaving the gear-wheel 10 free to revolve. It will thus be seen that the cushioned stop is in position to engage the gear-wheel 10 at the instant when the belt is shifted to stop the machine and is withdrawn at the instant when the belt-shifter is thrown to start the machine.

In order that the clutch 44 may be shifted so as to set the feed-rollers 25 and 26 of the die-press in operation during the time when the platen is at rest, means are provided for closing the clutch 44 simultaneously with the shifting of the belt-shifter to stop the machine. This clutch-closing device may be operated by any suitable part of the die-press and is here shown as controlled by the belt-shifter itself. Referring to Figs. 4 and 9, 90 is a lever pivoted at 91 to any suitable support and having its lower end provided with an antifriction-roller 92 in position to be engaged by a cam 93, formed on the belt-shifter 55, at the time when the belt-shifter is in position to stop the machine, as clearly shown in Fig. 4, the lever 90, however, being free from engagement with the belt-shifter when the latter is thrown into position to start the machine. Pivoted to the lever 90 at 92 is a bell-crank lever, one of whose arms 98 is connected by a suitable link to a draw-rod 94, the other arm 95 of said bell-crank lever carrying an antifriction-roller 96 in position to be engaged by an arc-shaped rib 97 on the outside face of the left-hand gear-wheel 10 of the die-press. This arc-shaped rib 97 extends through but a short arc on the gear-wheel 10 and is so positioned that it engages the antifriction-roller 96 on the arm 95 on the bell-crank at the instant when it is desired to start the feed-rollers into operation. The action of the rib 97 is to so rock the bell-crank lever on its pivot 92 as to depress the arm 98, and thereby effect a downward pull on the rod 94, which downward pull acts to close the clutch 44, and thus start the feed-rollers 25 and 26 into operation. The clutch 44 remains closed so long as the pull on the rod 94 is maintained and is opened when said pull ceases, as will be hereinafter more fully set forth, and this pull upon the rod 94 is maintained so long and only so long as the arc 97 is in engagement with the roller 96 on the bell-crank lever. The parts are in position for the arc 97 to actuate the draw-rod 94 to close the clutch 44 only when the shifter is in position to stop the machine, since the moment the shifter is thrown from right to left the lever 90 is freed from the cam part 93 upon the shifter, and thus permits the latter structure, including the bell-crank lever-arms 98 and 95 to rock away from the arc 97. Moreover, even though the shifter remain in the position shown in Fig. 4 the feed-rollers 25 and 26 will be operated only so long as the arc remains in con-

tact with the antifriction-roller 96. When said antifriction-roller 96 escapes from the arc 97, the spring on the clutch 44 will instantly throw the clutch open, causing an upward pull upon the draw-rod, causing the arm 95 of the bell-crank lever to fall downward, said downward or rocking action, however, being limited by a stop in the form of a rigid arm 99, projecting under the upper end of the lever 90 and the bell-crank lever. 75

Referring to Fig. 1^a, 44 is the free member of the clutch, which when shifted from right to left in the figure operates to engage the continuously-running member 44', keyed to the driving-shaft. 100 is a four-armed lever 80 one of whose arms is pivotally connected to the draw-rod 94, another of which is connected at 101 to the clutch, while still another arm extends out over the belt 43 and carries a brake-shoe 103. Two springs 104 85 and 105 act to normally throw the lever in such a position as to effect an upward pull upon the draw-rod 94 and to withdraw the female member 44 of the clutch from engagement with the male member 44' and at the same time depresses the brake-shoe 103 upon the belt 43. When, however, the downward pull is effected upon the draw-rod 94, as hereinbefore described, the clutch is closed and the brake 103 elevated out of engagement with the belt 43.

Referring now more particularly to Figs. 13, 15, and 16, 106 106 are a pair of ejector-plates resting in front of the platen 3 and just small enough to push through the hollow die 4 and being preferably similar in shape to the pad which is designed to be cut by said die. Pins 107 107 extend rearwardly through openings in the platen 3 and are connected, as by a cross-bar 108, to which is pivoted by a pin-and-slot connection 109 a lever-arm 110, keyed to a rock-shaft 111, rocking in suitable bearings on the lower edge of the platen. There is also keyed to this rock-shaft 111 a depending arm 112, preferably bearing an antifriction-roller 113. Keyed to a rock-shaft 114, turning in suitable bearings on the under part of the framework of the machine, is an arm 115, which extends rearwardly and has a downwardly inclined cam 116 located substantially beneath the antifriction-roller 113 on the arm 112. The rock-bar 114 extends outward on the left-hand side of the machine and on its outer end has an arm 117 keyed thereto, the upper end of which arm normally lies in a position to be engaged by the arc 97 on the gear-wheel 10 on the left-hand side of the machine, as viewed in Fig. 4.

By reference to Figs. 15 and 16 it will be observed that the parts are so timed that when the platen is open and in non-operative position, as shown in Fig. 15, the arc 97 is out of engagement with the arm 117 on the rock-shaft 114, but that when the platen is ad- 130

vanced to cut the pad, as shown in Fig. 16, the arm 117 is engaged by the arc 97, and thereby depressed, whereby the rock-shaft 114 is rocked so as to elevate the cam 116, 5 causing it to engage with the friction-wheel 113 and through the arm 112, the rock-shaft 111, and the arm 110 actuated the ejector-plates 106 106, so as to force the two pads which have been cut through and out of the 10 hollow cutter-die, as clearly illustrated in Fig. 16.

Operation: The operation of the device is as follows: The sheet of fibrous material being fed by any suitable carrier to a skiver 15 having a pattern-roller, say of the character illustrated in Fig. 2—i.e., with two cut-away or depressed portions 19 and two cylindrical portions 18—said skiver operates to skive out two cuts at each revolution of the pattern-roller, and as the sheet advances from 20 between the pressure and pattern rollers it is passed between the two feed-rollers 23 and 24, Fig. 2, and from thence to the feed-rollers 25 and 26 upon the die-press, passing downward 25 between said rollers and in front of the platen 3 and to the rear of the depending apron 45, the belts 48 passing over the feed-roller 25 and the idler-roller 47 assisting to properly guide the sheet. When the first 30 portion of the fibrous sheet has descended until it is substantially opposite the die 2, the vertical position of the feed-rollers 25 and 26 is adjusted by elevating or depressing the racks 30 through the medium of the crank-handle 38 and is retained in the adjusted position by the engagement of pawl 36 with the ratchet-wheel 35. When properly adjusted, the fibrous sheet will occupy the position opposite the die, as shown in Fig. 2—i.e., with 35 the skived-out portions 28 opposite the upper and lower edges of the die and the thickest portions 27 of the sheet substantially opposite the transverse central cutting-blade 4, as is clearly shown in Fig. 16. This adjustment 40 may be secured while the machine is at rest or while it is in motion, one of the great advantages of the adjustment of the feed-rollers shown being that an accurate adjustment can be secured while the machine is in motion, thereby correcting any slight inaccuracy 45 of the position of the skived sheet that may develop as the pads are cut. Power being applied, the platen 3 is advanced from the position shown in Fig. 15 to that shown 50 in Fig. 16, thereby forcing the fibrous sheet against the sharp edge of the die and cutting two pads at a single stroke. As the platen is advanced the swinging apron 45 is thrown forward, and the cut-away portion 46 permits it to swing slightly past and to the outside of the die, as shown in Fig. 16. This swinging motion of the apron is accomplished 55 against the tension of the spring 120, Fig. 12, which bears upon one arm 121 of a bell-crank lever, the other arm of which, 122, is

rigidly connected to the apron, and as soon as the platen is withdrawn the spring 120 again throws the swinging apron 45 into the position shown in Figs. 2 and 15. Just at the instant when the platen has pressed the fibrous sheet against the cutting edge of the die with sufficient force to effect the cut the pushing blades or followers 106 106 are caused to drive the pads through the hollow die and eject them therefrom, as is clearly shown in Fig. 16. This advance of the pusher or follower-blades 106 is effected by the contact with the arced rib 97 with the lever-arm 117, which rocks the shaft 114, elevating the lever-arm 115 until it contacts with an antifriction-roller 113 on the arm 112, thereby rocking the shaft 111 and throwing forward the arm 110, which actuates the pusher blades or followers 106. The left-hand gear-wheel 10, having advanced to a point where the lever-arm 117 escapes from the arced rib 97, the parts return to the position shown in Fig. 15 through the action of gravity. Immediately after the arm 117 has escaped from the arced rib 97 the projecting stop-lug 85 upon the right-hand gear-wheel 10 (see Fig. 4) contacts with the front face of the depending lever 86 and forces it against the tension of spring 87 in contact with the shoulder 84 on the bell-crank lever 81, thereby bringing the machine to a stop against the yielding cushion afforded by the spring 87. Just before the stop-lug 85 contacts with the lever 86, however, the driving-belt has been shifted from the pulley 15 to the pulley 16 by the action of the antifriction-roller 80 on the right-hand gear-wheel 10, which has struck the arced-shaped portion of the lever 65 and thrown it rearward, thereby effecting a pull through the bell-crank lever 59 upon the belt-shifter 55, and thus withdrawing the shifter to the position shown in Fig. 4 against the tension of its spring 58. The parts being thrown into this position, the lug 67 (see Fig. 4a) is thrown rearward or toward the skiver until its shoulder 68 engages with the shoulder 69 in the slot 70, formed in the fork 71. (Shown in dotted lines in Fig. 4.) The engagement of the shoulder 68 with the shoulder 69 acts to retain the parts in position, (shown in Fig. 4,) but against the tension of the belt-shifting spring 58. The action of the belt-shifter in moving from left to right causes the cam 93 upon said shifter to engage the lever 90, as shown in Fig. 4, and rock its upper end toward the left-hand gear-wheel 10, thus throwing the antifriction-roller 96 upon the bell-crank lever 95 into position to be engaged by the arced rib 97 on the left-end gear-wheel 10, thereby rocking the bell-crank lever 95, so as to effect a downward pull, which acts to close the clutch member 44 with the clutch member 44', thereby starting the belt 43 and simultaneously lifting the 125 130 135 140 145 150 155 160 165 170 175 180 brake-shoe 103 from contact with said belt, the downward pull on the draw-rod 94 being effected against the tension of springs 104 105, as will be clearly understood from an inspection of Fig. 1^a. It will be understood that the feed-rollers 25 and 26 were at rest during the time occupied by the platen in advancing toward and withdrawing from the cutter-die, and that, therefore, the sheet of fibrous material that was being continuously fed from the feed-rollers 23 and 24 on the skiver has sagged materially from the position shown in Fig. 2. It is essential, however, that the action of the platen in forcing the sheet of skived material against the die should be perfectly timed with the skiving action of the skiver, and in order that this should occur it is essential that there should be two vibrations of the platen 2 to one revolution of the pattern-roller on the skiver and that there should be consumed by the cutting action of the die in these two vibrations of the platen the exact length of the fibrous sheet that would be skived by a single revolution of the pattern-roller. This result is effected through the medium of the trip-lever 74, Fig. 4, and the two tripping-lugs 79, fixed to the axis of the pattern-roller and revolving therewith. Each of the lugs 79 acts to trip the lever 74 at each revolution of the pattern-roller—*i. e.*, the tripping-lever 74 is tripped twice at each revolution of said roller. The tripping of the lever 74 operates to lift the lug 67 upon the tilting lever 62, so as to free the shoulder 68 from the shoulder 69, thereby permitting the spring 58 to throw the belt-shifter from the position shown in Fig. 4 to the left, so as to bring the driving-belt 17 onto the pulley 15, through which the mechanism is set in motion to vibrate the platen. A single revolution of the gear-wheels 10 effects a complete vibration of the platen, and at each revolution the belt is again shifted from the pulley 15 to the pulley 16, as above described, and the platen brought to rest, when it is again tripped by the second lug 79 on the skiver and the operation is repeated. The slack which has occurred in the fibrous sheet between the feed-rollers on the skiver and those upon the die-press during the time when the platen is at rest is taken up without strain upon the fibrous sheet by the feed-rollers 25 and 26. During the time when these rollers are at rest, as hereinbefore described, the clutch-tooth 50 upon the idling-sprocket 49 is advanced a part of a revolution in front of the clutch-tooth 51 on the pulley 42, keyed to the shaft of the feed-roller 25, and when the pull is effected upon the draw-rod 94 to throw the clutch members 44 and 44' into engagement, Fig. 1^a, the driving-belt 43, Fig. 1, for said rollers is started up at a speed exceeding that of the sprocket-chain 52, extending from the shaft of the feed-roller 24 on the skiver to the

idling sprocket-wheel 49. The result is that the tooth 51 upon the pulley 42 quickly overtakes the clutch-tooth 50 upon the idling sprocket-wheel 49, turning the rollers 25 and 26 quite rapidly, and thereby taking up the slack which occurred while said rollers 25 and 26 were at rest. At the instant, however, when the slack is taken out of the fibrous sheet the clutch-tooth 51 contacts with the clutch-tooth 50, and thence forward the belt 43 can drive the feed-rollers 25 and 26 only as fast as it is permitted to advance by the tooth 51, which moves at the same rate as the feed-rollers 23 and 24 upon the skiver, the slip of the driving-belt 43 for the feed-rollers 25 and 26 permitting this action. It will thus be seen that the feed of the feed-rollers 25 and 26, though intermittent, is in the long run precisely the same in amount as the continuously-operating feed-rollers 23 and 24 upon the skiver. It follows that if the skived sheet has once been adjusted, so as to bring it into proper position in front of the cutter-die, as shown in Fig. 15, it will continue to thus position the parts during the entire operation of the machine.

It will be seen that by the invention above described there is combined into one complete operative structure a skiving-machine and a cutting-machine, the one operating continuously, and the other operating intermittently, and that nevertheless the action of the intermittently-operating die-press is absolutely under the control of the continuously-operating skiver, so that the cutting-machine or die-press effects its cut from the proper part of the skived sheet. Moreover, it will be seen that the entire die-press is made up of a very small number of parts—viz., the die, the platen, and the intermittently-operating feed-rollers—and that the simple driving-gear for effecting the vibration of the platen at the same time operates to control the stopping of the die-press without serious strain to the parts, the starting of the feed-rollers, and the ejection of the cut pads from the die, while the skiver operates not only to skive the sheet of fibrous material, but to effect the starting of the mechanism for vibrating the platen in perfect time with the skiver and also to control the action of the intermittently-operating feed-rollers upon the die-press, to the end that they shall effect the feeding of the same length of the fibrous sheet in a given time as is effected by the continuously-operating feed-rollers of the skiver and without strain upon said sheet.

What is claimed is—

1. In pad-making apparatus, the combination of skiving mechanism, pad-cutting mechanism, and feed devices controlled by both of said mechanisms.
2. In pad-making apparatus, the combination of skiving mechanism, pad-cutting mechanism, and intermittently-operating

- feed devices controlled by both of said mechanisms.
3. In pad-making apparatus, the combination of skiving mechanism, and pad-cutting mechanism, with continuously-operated feed devices on the skiving mechanism, and intermittently-operated feed devices on the pad-cutting mechanism.
4. In pad-making apparatus, the combination of skiving mechanism, and pad-cutting mechanism, with continuously-operated feed devices on the skiving mechanism, and intermittently-operated feed devices on the pad-cutting mechanism controlled by the feed devices on the skiving mechanism.
5. In pad-making mechanism, a skiving device, a die, a platen, and intermittently-operating feed devices advancing a sheet of material from said skiving device to and between said die and platen.
6. In pad-making apparatus, the combination of a skiving device, an intermittently-operating pad-cutting mechanism, means feeding a skived sheet of material from said device to said mechanism, starting and stopping means for said mechanism, the starting means controlled by said device, and the stopping means controlled by said mechanism.
7. In a pad-cutting device, the combination of a die and a vibratory platen, with intermittently-operating feed-rollers for delivering a sheet of material between said die and platen, and means for adjusting said rollers toward and from said die and platen.
8. In a pad-cutting device, the combination of a die and vibratory platen, with intermittently-operating feed-rollers for delivering a sheet of material between said die and platen, and means simultaneously stopping the platen and starting the feed-rollers.
9. In a pad-cutting device, the combination of uniformly-operating sheet-feeding means, intermittently-operating feed-rollers, a check device for said rollers controlled by said means, and an intermittently-operating pad-cutting mechanism.
10. In a pad-cutting device, the combination of uniformly-operating sheet-feeding means, intermittently-operating feed-rollers, a check device for said rollers controlled by said means, an intermittently-operating pad-cutting mechanism, and starting and stopping means for said feed-rollers controlled by said mechanism.
11. In a pad-cutting device, the combination of a die or cutter, a vibratory platen, power-actuated means for vibrating said platen, feed mechanism for supplying sheet material, power connections for operating the same, and a device actuated at each vibration of the platen for cutting off the power from the platen-vibrating mechanism and turning on the power to the feed mechanism.
12. In a pad-cutting device, the combination of intermittently-operated pad-cutting mechanism, intermittently-operating feed mechanism for supplying sheet material thereto, continuously-operating means advancing sheet material to said feed mechanism, and a speed-arrester controlled by said means and governing said feed mechanism.
13. In a pad-cutting device, the combination of intermittently-operated pad-cutting mechanism, a pair of intermittently-operated feed-rollers for supplying sheet material to said pad-cutting mechanism, means advancing said sheet material to said feed-rollers, and power devices for driving said feed-rollers faster than said means, and a control device governed by said means and checking the speed of said rollers at a predetermined point.
14. In a pad-cutting device, the combination of intermittently-operated pad-cutting mechanism, a pair of feed-rollers, a drive-pulley therefor having a clutch-tooth, means supplying sheet material to said feed-rollers and actuating a revolving part having a clutch-tooth in the path of the clutch-tooth on the said pulley.
15. In a pad-cutting device, intermittently-operated pad-cutting mechanism, intermittently-operated feed-rollers for supplying sheet material thereto, a driving-pulley for said rollers, a clutch-tooth rigidly connected to and revolving with said rollers, means continuously supplying sheet material to said rollers, and a revolving member having a part projecting in the path of said clutch-tooth, said revolving member moving at a continuous and uniform rate of speed.
16. In a pad-cutting device, an intermittently-operated pad-cutting mechanism, intermittently-operated feed-rollers for supplying sheet material to said mechanism, continuously-operated feed-rollers supplying sheet material to said intermittently-operated rollers, a driving-pulley for said intermittently-operated rollers, an idler-wheel loose on the shaft of said rollers, a lug on said idler-wheel in the path of and in front of a corresponding lug on said driving-pulley, and a gearing connection between said continuously-operated rollers and said idler-wheel.
17. In pad-making apparatus, the combination of a skiving-machine, continuously-operating feed-rollers receiving material from said skiving-machine, an intermittently-operated pad-cutting mechanism, intermittently-operated feed-rollers receiving sheet material from said continuously-operating rollers and supplying it to said pad-cutting mechanism, and a continuously-moving part moving in time with said continuously-operating rollers and traveling in the path of and in front of an intermittently-moving part moving in time with said intermittently-moving rollers.

18. In a pad-cutting device, the combination of a stationary die, a vibrating platen, power-driven mechanism for vibrating said platen, intermittently-operating feed-rollers for feeding sheet material between said platen and die, means for applying power to drive said rollers, and devices actuated by said power-driven mechanism to stop movement of the platen and to set said means in operation after each vibration of the platen to drive said rollers. 5
19. In a pad-cutting device, the combination of pad-cutting mechanism, feed-rollers supplying sheet material thereto, yielding bearings for said rollers, and means operable during the operation of the machine for adjusting said bearings relatively to said cutting mechanism. 15
20. In a pad-cutting device, the combination of intermittently-operating pad-cutting mechanism, intermittently-operating feed-rollers therefor located above said mechanism, vertically-adjustable bearings for said rollers, and means operable during the operation of the machine for adjusting said bearings relatively to said cutting mechanism. 25
21. In a pad-cutting device, the combination of intermittently-operating pad-cutting mechanism, feed-rollers supplying sheet material to said mechanism and located above the same, bearings for said rollers, vertically-adjustable rack-bars for supporting said bearings, a shaft having pinions engaging said rack-bars, and means for revolving said shaft. 35
22. In a pad-cutting device, the combination of pad-cutting mechanism, feed-rollers above the same for feeding sheet material thereto, bearings for said feed-rollers, two vertically-adjustable rack-bars supporting said bearings, a shaft bearing pinions engaging said rack-bars, a ratchet on said shaft, and a pawl for engaging said ratchet. 40
23. In a pad-cutting device, the combination of intermittently-operating pad-cutting mechanism, a pair of intermittently-operated feed-rollers, a pulley for driving the same connected to a clutch member normally loose on the driving-shaft, intermittently-operating driving means for said pad-cutting mechanism, and a device operated by said driving means upon each stroke of the pad-cutting mechanism to shift said clutch member into operative connection with the driving-shaft. 45
24. In a pad-cutting die-press, the combination of a stationary cutting-die, a platen vibrating to and from the same, power-driven mechanism intermittently vibrating said platen, a pair of feed-rollers located above said die and platen intermittently operable to supply sheet material thereto, a driving-pulley therefor, forming a loose member of a clutch, a continuously-driven pulley forming the other part of said clutch, 55
- and means automatically operated to open said clutch when the platen is vibrated and close the clutch at the end of each vibration of the platen. 60
25. In a pad-making apparatus, the combination of a skiving-machine having a pattern-surface, a die-press having a stationary die and a vibratory platen, power mechanism for intermittently vibrating said platen, and means controlled by the pattern-surface 70 on the skiving-machine and applying power to said power mechanism. 75
26. In a pad-making apparatus, the combination of a skiving-machine, a die-press having a stationary cutting-die and a vibratory platen for cutting pads from the skived material, power-driven mechanism for vibrating said platen, a belt-shifter for applying power to or withdrawing it from said mechanism, and means controlled by said skiving-machine and normally acting to retain said belt-shifter in position to withdraw power from said power-driven mechanism. 80
27. In pad-making apparatus, the combination of a skiving-machine, a pad-cutting die-press having a die and a vibratory platen and power-driven mechanism for vibrating said platen, a belt-shifter having a spring normally throwing said shifter so as to apply power to said mechanism, means operated 90 by said mechanism at each vibration of the platen to throw said shifter against the tension of its spring and thereby withdraw power from said mechanism, a catch normally holding the shifter in said last-named position 95 against the tension of its spring, and a trip controlled by the skiver and freeing the belt-shifter and permitting it to be operated by its spring to again apply power to the driving mechanism. 100
28. In a pad-cutting device, the combination of intermittently-operated pad-cutting devices, intermittently-operating power-driven mechanism therefor, means alternately applying power to and withdrawing it 110 from said mechanism, and a yielding stop for said mechanism controlled by said means. 105
29. In a pad-cutting apparatus, the combination of intermittently-operating pad-cutting devices, intermittently-operating power-driven mechanism therefor, means alternately applying power to and withdrawing it from said mechanism, a yielding stop for said mechanism, and connections between said means and said stop whereby the stop is 115 thrown into operative position when the power is withdrawn and out of operative position when the power is applied. 120
30. In a pad-cutting apparatus, the combination of a stationary die or cutter, a vibratory platen, power-driven mechanism vibrating said platen, a belt-shifter alternately applying power to and withdrawing it from said mechanism, a yielding stop for said mechanism, and connections between said 125 130

stop and belt-shifter whereby the same is withdrawn from its operative position when the said shifter is operated to apply power to said mechanism.

5 31. In a pad-cutting apparatus, the combination of a stationary die or cutter, a vibratory platen, an intermittently-operated power mechanism for vibrating said platen, a belt-shifter operable to apply power to and withdraw it from said mechanism, and a vibratory stop for said mechanism operatively connected to said belt-shifter.

10 32. In a die-cutting press, the combination of a stationary hollow die, a vibratory platen, and pad-ejecting means carried by said platen, and operative upon each vibration thereof.

15 33. In die-cutting apparatus, a hollow stationary cutting-die, a platen vibrating to and from said die, means feeding sheet material between said die and platen, a pad-ejector carried by said platen, power mechanism for vibrating said platen, and connections between said mechanism and said pad-ejector 20 for operating said ejector on each vibration of the platen.

25 34. The combination of skiving mechanism cutting transverse channels in a continuous sheet or strip of material, and a pad-cutting device cutting pads from said channeled sheet or strip.

30 35. The combination of skiving mechanism, and a pad-cutting device, with intermittently-operating feeding means receiving the 35 skived material from said mechanism and delivering it to the pad-cutting device.

35 36. The combination of skiving mechanism and pad-cutting mechanism, a continuous-feed device on the skiving mechanism and an intermittent-feed device on the pad-cutting mechanism receiving the skived material from said continuous-feed device and delivering the same intermittently to said pad-cutting mechanism.

40 37. The combination of skiving mechanism and a pad-cutting device, with revoluble feed means receiving the skived material from said mechanism and delivering it to the pad-cutting device, said means being controlled by both the skiving mechanism and cutting device.

45 38. The combination of skiving mechanism and a pad-cutting device with continuous feed means on the skiving mechanism and intermittent-feed means on the cutting device

receiving the skived material from the said continuous feed and delivering the same intermittently to said cutting device both of said feeding means controlled by said skiving mechanism and said cutting device. 60

39. The combination of skiving mechanism and a pad-cutting device, with intermittently-operating feed-rollers receiving the skived material from said skiving mechanism and intermittently delivering the same to 65 said cutting device, and means for adjusting said feed-rollers toward and from said device.

40. The combination of skiving mechanism and a pad-cutting device with intermittently-operated feed-rollers receiving the 70 skived material from said mechanism and delivering it to the pad-cutting device, and means simultaneously stopping the cutting device and starting the feed-rollers.

41. The combination of skiving mechanism and an intermittently-operated pad-cutting device with feeding means receiving the skived material from said mechanism and delivering it to the pad-cutting device. 75

42. The combination of skiving mechanism and intermittently-operated pad-cutting mechanism, a pair of intermittently-operated feed-rollers for supplying the skived material to said pad-cutting device, means continuously advancing said skived material to said 80 feed-rollers, power devices for driving said feed-rollers faster than said advancing means, and a control device governed by said advancing means and checking the speed of 85 said rollers at a predetermined point. 90

43. The combination of skiving mechanism and an intermittently-operated pad-cutting device, a pair of intermittently-operated feed-rollers receiving the skived material from said mechanism and delivering it to 95 said cutting device, a pulley for driving said rollers connected to a clutch member normally loose on the driving-shaft, driving means for said pad-cutting device, and a device operated by said driving means upon 100 each stroke of the pad-cutting device to shift said clutch member into operative connection with the driving-shaft.

In testimony whereof I have signed this specification in the presence of two subscribing witnesses. 105

GUSTAV GOLDMAN.
